UNITED STATES PATENT OFFICE.

LEWIS L. FOSTER, OF GOVANS, MARYLAND, ASSIGNOR OF ONE-HALF TO JOHN H. RUEHMLING, OF BROOKLYN, NEW YORK.

INTERNAL-COMBUSTION ENGINE.

1,255,730.

Specification of Letters Patent.

Patented Feb. 5, 1918.

Application filed September 13, 1917. Serial No. 191,238.

To all whom it may concern:

Be it known that I, LEWIS L. FOSTER, a citizen of the United States, residing at Govans, in the county of Baltimore and State of Maryland, have invented certain new and useful Improvements in Internal-Combustion Engines, of which the following is a specification.

This invention relates to an improved internal combustion engine and has as its primary object to provide a construction wherein in a firing stroke of the piston will occur at each half revolution of the engine crank shaft so that there will be no idle stroke of the said piston.

The invention has as a further object to provide a construction wherein the engine will be fired at each side of the piston so that the piston will thus be propelled in its movement in opposite directions.

A still further object of the invention is to provide an arrangement wherein complementary compression chambers will be employed for compressing the fuel mixture prior to its introduction into the ignition chambers of the engine.

The invention has as a further object to provide a construction wherein the intake and exhaust of the engine will be controlled by a single sleeve valve movable with the piston of the engine.

A further object of the invention is to provide an arrangement wherein the cylinders of the engine as well as the sleeve valve will be provided with removable heads or caps so that access may be easily gained to the interior thereof.

And the invention has as a still further object to provide an engine employing relatively long connecting rods to thus minimize the lateral or side thrust of the piston upon the working cylinder of the engine.

Other and incidental objects will appear as the description proceeds and in the drawings wherein I have illustrated the preferred embodiment of the invention and wherein similar reference characters designate corresponding parts throughout the several views:

50 Figure 1 is a fragmentary vertical sectional view of my improved engine showing the piston at the top of its stroke,

Fig. 2 is a similar view showing the piston at the bottom of its stroke,

Fig. 3 is a fragmentary sectional view 55 showing the piston in position for exhaust of the upper firing chamber of the engine,

Fig. 4 is a detail perspective view of the working cylinder of the engine and showing the spider employed for supporting the said 60 cylinder upon the outer cylinder or casing of the engine,

Fig. 5 is a vertical sectional view taken on the line 5—5 of Fig. 2 and looking in the direction of the arrows, this view showing 65 the manner in which the piston is connected with the engine crank shaft as well as the mounting of the said shaft,

Fig. 6 is a transverse sectional view taken on the line 6—6 of Fig. 2 and looking in the 70 direction of the arrows, this view showing the mounting of the spider which supports the working cylinder of the engine,

Fig. 7 is a transverse sectional view taken on the line 7—7 of Fig. 2 and looking in the 75 direction of the arrows, this view particularly showing the arrangement of the port employed for supplying oil to the engine piston, and

Fig. 8 is a transverse sectional view taken 80 on the line 8—8 of Fig. 2 and particularly showing the intake port of the upper firing chamber of the engine as well as the exhaust port of the engine.

In carrying out the invention, my improved engine is formed with a crank case 85 which, as usual, is preferably constructed in sections bolted or otherwise secured together. Journaled within the crank case is the engine crank shaft 11 provided with 90 complementary cranks 12 which extend in the same direction. The shaft is equipped at one end with a suitable fly wheel 13. Mounted upon the crank case is the fixed outer cylinder or casing 14 of the engine. This 95 cylinder is open at its ends and at its lower extremity is provided with an annular flange 15 to which is connected a bottom plate or cap 16 closing the adjacent end of the said cylinder and seating against the crank case 100 10. Extending through the said flange to connect the plate 16 thereto as well as to secure the cylinder 14 to the crank case are a plurality of bolts or other suitable fastening devices 17. As particularly shown in 105 Fig. 2 of the drawings, the crank case is, beneath the plate 16, provided with a suitable opening and projecting from the said plate

through this opening is an arm or web 18 provided at its lower extremity with a bearing 19 to support the crank shaft 11.

Suspended within the upper extremity of 5 the outer cylinder 14 axially thereof is a working cylinder 20 which is also open at its ends. The cylinder 20 is provided with a water jacket 21 connected with the said cylinder at opposite sides thereof by vertical webs 22 which, as particularly shown in 10 Figs. 2 and 5 of the drawings, terminate in spaced relation to the lower end of the said water jacket. The purpose of these webs will presently appear. Closing the lower 15 extremity of the cylinder 20 is a removable end cap 23 preferably screw threaded upon the said cylinder. Screw threaded into the upper extremity of the cylinder is a hollow packing cylinder or plug 24 formed at its 20 upper end with a lateral annular flange 25 overlying the water jacket 21 to close the adjacent end thereof. The plug 24 is provided with an axial sleeve 26 terminating at its upper extremity in an extension 27 25 upon which is screw threaded a spider 28. Locking the spider upon the said extension are a plurality of bolts or other suitable fastening devices 29. The spider 28 is, as shown in detail in Fig. 4 of the drawings, 30 preferably provided with quadrantly spaced radial arms 30 which overhang the upper extremity of the outer cylinder 14 and, at their outer ends, seat upon an annular flange 31 projecting laterally from the adjacent 35 end of the said cylinder. Securing the arms to the said flange are bolts or other suitable fastening devices 32. As will now be clear, the spider 28 will thus rigidly support the working cylinder 20 of the engine within the 40 outer cylinder 14 thereof.

Snugly fitting between the outer cylinder 14 and the inner cylinder 20 to surround the water jacket of the said inner cylinder is a slidably mounted sleeve valve or cylinder 33. This cylinder is, as particularly 45 shown in Fig. 2 and similar sectional views of the drawings, provided with longitudinally extending slots 34 which slidably receive the arms 30 of the spider 28. The 50 spider arms therefore serve to hold the cylinder 33 against rotation. Closing the lower end of the said cylinder is a removable end cap 35 preferably screw threaded into the said cylinder and similarly connected with 55 the upper end of the cylinder is a removable end cap or head 36. Secured to this head for movement with the cylinder 33 is a piston 37 slidably fitting within the working cylinder 20 of the engine. The rod 38 of 60 this piston is slidably received through the sleeve 26 of the packing cylinder or plug and, at its upper extremity, is screw threaded into a boss 39 formed axially upon the inner side of the head 36 for thus detachably connecting the said piston with the 65

head. Suitable packing rings 40 are mounted upon the piston, the cylinder 33 and the water jacket 21, as may be found necessary. Packing rings 41 are also mounted upon the piston rod 38 to bear within the sleeve 26 of the packing cylinder 24. This provides an effective arrangement for forming a tight joint between the piston rod and the said cylinder and a construction eliminating the use of a stuffing box. 70 75

Formed on the outer side of the head 36 of the cylinder 21, are spaced half-bearing blocks 42 with which are arranged to coat half-bearings 43 for receiving a cross pin 44. This pin is, as particularly shown in 80 Fig. 5 of the drawings, held against longitudinal movement by spaced collars 45 arranged to abut the bearings of the head and detachably connected to the extremities of the said pin are connecting rods 46 which 85 project through suitable openings 47 in the crank case and are secured to the cranks 12 of the crank shaft 11. Reciprocation of the piston 37 will thus act to reciprocate the cylinder or sleeve valve 33 and consequently 90 actuate the connecting rods 46 to turn the crank shaft 11. In this connection, attention is directed to the fact that by the arrangement shown, relatively long connecting rods are employed to consequently minimize 95 the lateral or side thrust of the piston against the walls of the working cylinder 20 of the engine. The crank case is, at opposite sides of the openings 47, formed with parallel under-cut flanges 48 and slidably 100 engaging with the said flanges to close the said openings are plates 49 through which the connecting rods 46 are loosely fitted. The plates 49 will therefore slide upon the same flanges as the connecting rods move 105 with the crank shaft and will prevent splashing of the oil through the openings 47. 110

Leading through one of the slots 34 at one side of the cylinder 33 is a water inlet pipe 50 which is fitted through the adjacent arm 30 of the spider 28 as well as through the flange 25 of the packing cylinder or plug 24 and communicates with the upper extremity of the water jacket 21 at the said side of the jacket. Communicating in a similar manner with the upper extremity of the water jacket at its opposite side, is an outlet pipe 51 which is carried through the slot 34 of the cylinder 33 diametrically opposite the slot receiving the pipe 50. The 115 pipes 50 and 51 may be connected with any suitable circulating system and as will now be observed, the water will be introduced into the water jacket at one side of the webs 28 of the said jacket and will be carried from the jacket at the opposite sides of the said webs. The function of these webs, previously referred to, now therefore becomes apparent, since it will be seen that said webs will cause the water within the water 120 125 130

jacket to circulate the full length thereof in order that the water may flow from the pipe 50 beneath the lower ends of the webs to be discharged at the pipe 51. Effective cooling 5 of the working cylinder of the engine will thus be accomplished.

It is now to be observed that a firing chamber is provided within the working cylinder 20 at each side of the piston 37 and, 10 for convenience, such firing chambers have been indicated at 52 and 53 respectively, the chamber 52 being the lower firing chamber and the chamber 53 being the upper firing chamber. Furthermore, it will be noted 15 that a chamber 54 is provided within the outer cylinder 14 below the lower end of the cylinder 33 and that a second chamber 55 is provided within the lower extremity of the cylinder 33 below the adjacent end of 20 the working cylinder 20. These chambers 54 and 55 constitute, as shall presently appear, compression chambers for the fuel mixture. At its lower extremity, the outer cylinder 14 is, at the adjacent side thereof, 25 formed to provide a transfer passage 56 leading from the lower end of the chamber 54 and entering through the cylinder 20 to communicate with the upper firing chamber 53. The wall of the cylinder 33 is, at the 30 lower end of the said cylinder, provided with an internal slot or transfer passage 57 arranged at the side of the said cylinder opposite the passage 56 and adapted to communicate with a passage 58 formed through 35 the wall of the working cylinder 20 at the lower end of the firing chamber 52. The chamber 54 thus forms a compression chamber for the upper firing chamber 53, while the chamber 55 forms a compression chamber 40 for the lower firing chamber 52. In this connection, it will be noted that the presence of the piston rod 38 within the upper firing chamber will cause the cubic volume of the said chamber to be somewhat less than that 45 of the lower firing chamber 52. Accordingly, the larger compression chamber 54 is 50 arranged to communicate with the upper firing chamber in order that a greater volume of fuel mixture may be introduced into the said chamber for equalizing the impulse at opposite sides of the piston. In order to further enhance this effect, the lower end of the packing cylinder or plug 24 is, as particularly shown in Fig. 2 and other similar 55 figures of the drawings, provided with a channeled face to accordingly increase the cubic volume of the said chamber.

The passage 58 in the lower end of the working cylinder 20 extends through the 60 outer cylinder 14 and, at its outer end, receives a spark plug, as conventionally shown at 59, this plug being screw threaded into the cylinder 14. Formed through this cylinder as well as the working cylinder 20 at a 65 point above the passage 58 is a passage 60

communicating with the upper firing chamber 53. Screw threaded upon the cylinder 14 in the outer end of the said passage is a spark plug, as conventionally shown at 61. Formed through the said cylinder at a point 70 midway between the passages 58 and 60, is an exhaust passage 62 in the outer end of which is fitted an exhaust pipe 63 screw threaded upon the cylinder 14. As shown in Figs. 7 and 8 of the drawings, the portions of the passages 56, 60 and 62 which extend through the water jacket 21 and cylinder 20 are formed with suitable webs so that the packing rings of the piston as well as any packing rings of the cylinder 33 80 moving over the passages, cannot spring into engagement with the walls thereof. The passage 58 is provided with a similar web. Formed in the cylinder 14 at a point below the passage 58 is an intake passage 85 64 with which may be connected a suitable carbureter, as conventionally illustrated at 65. The passages 58, 60, 62 and 64 are arranged in vertical alinement. Formed in one side of the cylinder 33 adjacent its lower 90 extremity is an intake passage 66. The adjacent side of this cylinder is further provided with vertically spaced passages 67 and 68 respectively. The passages 66, 67 and 68 are also arranged in vertical alinement and 95 in the same vertical plane with the passages 58, 60, 62 and 64 of the cylinders 14 and 20. Formed in the cylinder 33 at the side thereof opposite the passage 62 is an intake passage 69. 100

It will now be assumed that a charge of fuel mixture has been introduced into the firing chamber 52 and that the piston 37 is, as shown in Fig. 2 of the drawings, at the bottom of its stroke and moving upwardly 105 under the momentum of the fly wheel of the engine. The passage 67 of the valve 33 being in register with the passage 58, the charge of fuel mixture in the firing chamber 52 will be fired by the plug 59 to drive the 110 piston upwardly. As the piston thus moves upwardly, the passage 67 will be brought into register with the exhaust passage 62 to exhaust the fired charge from the said chamber. Since the valve 33 is arranged to move 115 with the piston, it will be observed that as the said valve thus moves upwardly with the piston that a partial vacuum will be created by the valve within the compression chamber 54. Consequently, as soon as the 120 lower end of said valve passes over the intake passage 64, as shown in Fig. 1, a charge of fuel mixture will be drawn into the said compression chamber from the carbureter 65. After the piston has reached the top of 125 its stroke ready to start downwardly, as shown in Fig. 1, it will be further assumed that a charge of fuel mixture has been introduced into the firing chamber 53. The passage 68 of the cylinder 33 being then in 130

register with the passage 60, the said charge will be fired by the plug 61 to drive the piston downwardly. Downward movement of the said piston will then shift the passage 68 into register with the exhaust passage 62, as shown in Fig. 3, for exhausting the upper firing chamber. The passage 67 will therefore provide a spark and exhaust port for the lower firing chamber 52 while the 10 passage 68 will provide a spark and exhaust port for the upper firing chamber 53. Downward movement of the valve 33 with the piston 37 will cause the said valve to compress within the chamber 54 the charge 15 of fuel mixture therein so that this valve thus also provides a compression cylinder. Such compressed charge will be held within the said chamber until the valve 33 has reached the bottom of its stroke, as shown 20 in Fig. 2, when the intake passage 69 of the said valve for the upper firing chamber will be brought into register with the passage 56. The compressed charge will then be forced through this passage 56 into the upper 25 firing chamber. Downward movement of the valve 33 will also cause the creation of a partial vacuum within the compression chamber 55. This partial vacuum will continue to exist until the valve has reached the 30 bottom of its stroke, when the intake passage 66 of the said valve will be brought into register with the passage 64 so that a charge of fuel mixture will then be drawn in through the said passages into the said chamber. As the piston 37 again moves 35 upwardly, the charge of fuel mixture in the upper firing chamber will be compressed by the piston. At the same time the charge of fuel mixture within the compression chamber 55 will be compressed by the valve 33. Movement of the piston to the top of its 40 stroke will then bring the slot 57 of the valve 33 into communication with the intake passage 58 of the lower firing chamber 52, as shown in Fig. 1, when the compressed 45 charge of fuel mixture within the compression chamber 55 will be forced into the said firing chamber. The charge of fuel mixture in the upper firing chamber will 50 then, as previously described, be fired for driving the piston downwardly and compressing the charge of fuel mixture drawn into the lower firing chamber 52, as well as the charge of fuel mixture drawn into the 55 compression chamber 54.

It will therefore be seen that each time a charge is fired in the lower firing chamber 52 to drive the piston upwardly, a charge of fuel mixture will be drawn into the compression chamber 54, a second charge of fuel mixture will be compressed within the compression chamber 55 and that a third charge of fuel mixture will be compressed within the upper firing chamber 53. In like manner, each time a charge is fired in the upper

firing chamber to drive the piston downwardly, a charge of fuel mixture will be drawn into the compression chamber 55, a second charge of fuel mixture will be compressed within the compression chamber 54 and a third charge of fuel mixture will be compressed within the firing chamber 52. Consequently, each charge of fuel mixture will, before it is fired, be initially compressed in one of the compression chambers 75 and then subsequently compressed within one of the firing chambers. In this way maximum results will be obtained from the fuel mixture. Furthermore, it will be noted that an explosion will occur within the working cylinder 20 of the engine at each half revolution of the engine crank shaft so that there will be no idle strokes of the engine piston. A maximum of energy will accordingly be developed by the engine. 85

Leading through the outer cylinder 14 into the working cylinder 20 of the engine is, as shown in detail in Fig. 7, an oil passage 70 in the outer end of which is fitted an oil pipe 71 from a suitable lubricating 90 tank. The cylinder 20 is, as shown in dotted lines in Fig. 7, provided with a passage 72 arranged in a horizontal plane with the piston 37 and adapted to be brought into register with the passage 70 when the piston 95 moves upwardly to the top of its stroke. Consequently, in this position of the piston, lubricant will be introduced through the passages 70 and 72 against the said piston each time the piston travels upwardly, for 100 effectively lubricating the piston.

It will therefore be seen that I provide a particularly effective construction for the purpose set forth and in this connection attention is directed to the fact that the piston of the engine may be removed at any time desired by simply displacing the head 36 of the sleeve valve or cylinder when the packing cylinder or plug 24 may be removed for displacing said piston. Also, the working cylinder of the engine may, in like manner, be removed at any time desired while access may be had to the compression chambers of the engine by simply removing the cap plates of the outer engine cylinder and 110 sleeve valve. 115

Having thus described the invention, what is claimed as new is:

1. An internal combustion engine including an outer cylinder, a working cylinder 120 supported therein, a piston mounted to reciprocate within the working cylinder, the working cylinder providing firing chambers at opposite sides of said piston, intake and exhaust ports for the said chambers, and a sleeve valve mounted to move with the piston between the said cylinders for opening and closing said ports.

2. An internal combustion engine including an outer cylinder, a working cylinder 130

supported therein, a piston mounted to reciprocate within the working cylinder, the said working cylinder providing firing chambers at opposite sides of said piston, 5 intake and exhaust ports for the said chambers, a sleeve valve mounted to slide between the said cylinders for opening and closing said ports, and a head carried by the said valve and connecting the piston therewith.

10 3. An internal combustion engine including a crank shaft, an outer cylinder, a working cylinder supported therein, a piston mounted to reciprocate within the working cylinder, the working cylinder providing

15 firing chambers at opposite sides of said piston, intake and exhaust ports for the said chambers, a sleeve valve connected with the piston and mounted to slide between the said cylinders for opening and closing said 20 ports, and a connection between the said valve and the said crank shaft.

4. An internal combustion engine including a crank shaft, an outer cylinder, a working cylinder supported therein, a piston 25 mounted to reciprocate within the working cylinder, the working cylinder providing firing chambers at opposite sides of said piston, intake and exhaust ports for the said chambers, a sleeve valve mounted to slide 30 between the said cylinders for opening and closing said ports, a head carried by said valve and connecting the valve with the piston, a cross pin mounted upon said head, and a connecting rod between the said cross 35 pin and the said crank shaft.

5. An internal combustion engine including an outer cylinder, a working cylinder arranged therein, a spider supporting the working cylinder upon the outer cylinder, 40 a piston mounted to reciprocate within the working cylinder, the said working cylinder providing firing chambers at opposite sides of said piston, intake and exhaust ports for the said chambers, and a sleeve valve mounted to move with the piston between the said cylinders for opening and closing the said ports and loosely receiving the arms of said spider.

6. An internal combustion engine including 50 an outer cylinder, a working cylinder supported therein, a packing plug closing the working cylinder, a piston mounted to reciprocate within the working cylinder and having the rod thereof slidably received 55 through said plug, the working cylinder providing firing chambers at opposite sides of the said piston, intake and exhaust ports for the said chambers, and a sleeve valve connected with the piston rod and mounted 60 to slide between the said cylinders for opening and closing said ports.

7. An internal combustion engine including 65 an outer cylinder, a working cylinder arranged therein, a packing plug closing the working cylinder, a spider connected to said

plug and having arms overhanging said cylinder for supporting the working cylinder in position, a piston mounted to reciprocate within the working cylinder and having a piston rod slidably received through said 70 plug, the working cylinder providing firing chambers at opposite sides of said piston, intake and exhaust ports for the said chambers, and a sleeve valve connected with the piston rod and mounted to slide between the 75 said cylinders for opening and closing said ports, the said valve being provided with slots loosely receiving the arms of said spider.

8. An internal combustion engine including 80 an outer cylinder, a working cylinder arranged therein and surrounded by a water jacket, a piston mounted to reciprocate within the working cylinder, the working cylinder providing firing chambers at opposite 85 sides of said piston, intake and exhaust ports for the said chambers, a sleeve valve connected with the piston and surrounding the said water jacket to slide within the outer cylinder for opening and closing said 90 ports, and circulating pipes for the water jacket operatively received through the said valve.

9. An internal combustion engine including 95 an outer cylinder, a working cylinder arranged therein, a water jacket surrounding the working cylinder, a packing plug closing the working cylinder and provided with a flange closing the said water jacket, a piston mounted to reciprocate within the 100 working cylinder and having a piston rod slidably received through said plug, the working cylinder providing firing chambers at opposite sides of said piston, intake and exhaust ports for the said chambers, and a 105 sleeve valve connected with the piston rod and surrounding said water jacket to slide within the outer cylinder for opening and closing said ports.

10. An internal combustion engine including 110 an outer cylinder, a working cylinder arranged therein, a water jacket surrounding the working cylinder, a piston mounted to reciprocate within the working cylinder, the working cylinder providing firing chambers at opposite sides of said piston, intake and exhaust ports for the said chambers, a spider having arms overhanging the outer cylinder and connected with the working cylinder for supporting the working cylinder in position, a sleeve valve connected with the piston and surrounding the said water jacket to slide within the outer cylinder for opening and closing said ports, the said 120 valve being provided with slots receiving 125 the arms of said spider, and circulating pipes for the water jacket received through said slots.

11. An internal combustion engine including 130 an outer cylinder, a working cylinder

6
supported therein, a piston mounted to reciprocate within the working cylinder, the working cylinder providing firing chambers at opposite sides of said piston, intake and exhaust ports for the said chambers, a sleeve valve connected with the piston and mounted to slide between the said cylinders for opening and closing said ports, the sleeve valve coacting with the cylinders to 5 provide compression chambers and being movable to establish communication between the said chambers and the intake ports of the said firing chambers respectively, and an intake port for the said compression 10 chambers, the sleeve valve being also operable to establish communication between the said last-mentioned intake port and the compression chambers.

12. An internal combustion engine including an outer cylinder, a working cylinder supported therein, a piston mounted to reciprocate within the working cylinder, the working cylinder providing firing chambers at opposite sides of said piston, intake and 20 exhaust ports for the said chambers, a sleeve valve connected with the piston and mounted to slide between the said cylinders for opening and closing the said ports, the said valve co-operating with the cylinders to provide compression chambers and being movable to establish communication between the said compression chambers and the intake ports of the firing chambers, and an intake 25 port for said compression chambers, the said valve being movable to selectively establish communication between the said last-mentioned intake port and the said compression chambers and to selectively draw in a fuel charge through the said last-mentioned port 30 into the said compression chambers.

13. An internal combustion engine including an outer cylinder, a working cylinder supported therein, a piston mounted to reciprocate within the working cylinder, the working cylinder providing firing chambers at opposite sides of said piston, intake ports for the said chambers, a common exhaust port for the said chambers, firing ports for the said chambers, and a sleeve valve connected with the piston and mounted to slide between the said cylinders for opening and closing said ports.

14. An internal combustion engine including an outer cylinder, a working cylinder supported therein, a piston mounted to reciprocate within the working cylinder, the working cylinder providing firing chambers at opposite sides of said piston, intake and exhaust ports for the said chambers, a sleeve valve connected with the piston and mounted to slide between the said cylinders for opening and closing said ports, the sleeve valve co-operating with the cylinders to provide compression chambers, and an intake 60 port for the said chambers, the sleeve valve 65

being movable for alternately compressing a charge of fuel mixture within one of the compression chambers and drawing in a charge of fuel mixture into the other of said compression chambers through the said last-mentioned intake port.

15. An internal combustion engine including an outer cylinder, a working cylinder supported therein, a packing cylinder closing the working cylinder and formed with an axial sleeve, a piston mounted to reciprocate within the working cylinder and having a piston rod slidably received through said sleeve, means carried by the piston rod for engagement within the sleeve 70 to provide a sealed joint between the rod and the sleeve, the working cylinder providing firing chambers at opposite sides of said piston, intake and exhaust ports for the said chambers, and a sleeve valve connected with the piston rod and mounted to slide between the said cylinders for opening and closing said ports.

16. An internal combustion engine including a working cylinder, a cylinder surrounding the working cylinder, a piston mounted to reciprocate within the working cylinder, the working cylinder providing firing chambers at opposite sides of said piston, intake and exhaust ports for the said chambers, and a sleeve valve mounted to move between the said cylinders for opening and closing said ports.

17. An internal combustion engine including a working cylinder, a cylinder surrounding the working cylinder, a crank shaft, a sleeve valve mounted to move between the said cylinders, and a piston mounted to reciprocate within the working cylinder and connected through said valve 90 with the crank shaft, the working cylinder providing firing chambers at opposite sides of the piston opened and closed by the said valve.

18. An internal combustion engine including a crank shaft, a working cylinder, a cylinder surrounding the working cylinder, a piston mounted to reciprocate within the working cylinder, the working cylinder providing firing chambers at opposite sides of said piston, intake and exhaust ports for the said chambers, a sleeve valve connected with the piston and mounted to move between the said cylinders for opening and closing said ports, and a connection between the outer end of the said valve and the crank shaft.

19. An internal combustion engine including a crank shaft, a working cylinder, a cylinder surrounding the working cylinder, a piston mounted to reciprocate within the working cylinder, the working cylinder providing firing chambers at opposite sides of said piston, intake and exhaust ports for the said chambers, a sleeve valve connected with the piston and mounted to move between the said cylinders for opening and closing said ports, and a connection between the outer end of the said valve and the crank shaft.

the piston and mounted to move between the said cylinders for opening and closing said ports, and connecting means between the said valve and the crank shaft extending at 5 opposite sides of the valve.

20. An internal combustion engine including a working cylinder, a cylinder surrounding the working cylinder, a piston mounted to reciprocate within the working cylinder, 10 the working cylinder providing firing chambers at opposite sides of the said piston and the piston rod extending through one of said chambers, intake and exhaust ports for the chambers, a sleeve valve mounted to 15 move between the cylinders for opening and closing said ports and coöperating with the said cylinders to provide a compression chamber exteriorly of the valve and adapted to communicate with the said firing chamber, 20 and a compression chamber interiorly of the valve and adapted to communicate with the other of the firing chambers.

21. An internal combustion engine including a working cylinder, a cylinder surrounding the working cylinder, a piston mounted to reciprocate within the working cylinder, 25 the working cylinder providing firing chambers at opposite sides of said piston, intake and exhaust ports for the said chambers, and 30 a sleeve valve mounted to move between the said cylinders for opening and closing said ports to permit the introduction of a fuel charge into one of the chambers and the compression of a fuel charge in the other 35 of said chambers at each stroke of the piston.

22. An internal combustion engine including a working cylinder, a cylinder surrounding the working cylinder, a piston mounted to reciprocate within the working cylinder, 40 the working cylinder providing firing chambers at opposite sides of said piston, exhaust ports for the said chambers, a sleeve valve mounted to move between the said cylinders and coöperating therewith to provide 45 compression chambers, intake ports from the compression chambers to the firing chambers, and an intake port for the said compression chambers, the valve being movable to open and close said ports and to draw in 50 a fuel charge into one of the compression chambers and compress a fuel charge in the other of the compression chambers at each stroke of the piston.

23. An internal combustion engine including a working cylinder, a cylinder surrounding 55 the working cylinder, a piston mounted

to reciprocate within the working cylinder, the working cylinder providing firing chambers at opposite sides of said piston, exhaust ports for the firing chambers, a sleeve valve 60 mounted to move between the cylinders and coöperating therewith to provide compression chambers, an intake port for the compression chambers, and intake ports to the firing chambers from the said compression chambers, the valve being movable for controlling 65 said ports to permit the introduction of a fuel charge into one of the firing chambers from one of the compression chambers and the compression of a fuel charge in the 70 other of the firing chambers at each stroke of the piston.

24. An internal combustion engine including a working cylinder, a cylinder surrounding the working cylinder, a piston mounted 75 to reciprocate within the working cylinder, the working cylinder providing firing chambers at opposite sides of said piston, exhaust ports for the firing chambers, a sleeve valve mounted to move between the cylinders and coöperating therewith to provide compression chambers, an intake port for the compression chambers, and intake ports to the firing chambers from the said compression chambers, the valve being movable 80 for controlling said ports to permit the introduction of a fuel charge into one of the firing chambers from one of the compression chambers and the compression of a fuel charge in the other of the firing chambers 85 as well as to draw in a fuel charge into one of the compression chambers and compress a fuel charge in the other of the compression chambers 90 at each stroke of the piston.

25. An internal combustion engine including a working cylinder, a cylinder surrounding the working cylinder, a piston mounted to reciprocate within the working cylinder, the working cylinder providing firing chambers at opposite sides of said piston, intake 100 and exhaust ports for the firing chambers, and a single sleeve valve mounted to move between the cylinders for opening and closing said ports and coöperating with the cylinders to provide compression chambers 105 adapted to communicate with the firing chambers through said intake ports and having such communication controlled by the valve.

In testimony whereof I affix my signature. 110

LEWIS L. FOSTER. [L.S.]
